CLAIM

The ornamental design for an electronic card for receiving information from a video screen, as shown and described.

DESCRIPTION

FIG. 1 is a top plan view of an electronic card for receiving information from a video screen showing our new design;

FIG. 2 is a side elevational view thereof;

FIG. 3 is a side elevational view thereof opposite that shown in FIG. 2;

FIG. 4 is an end elevational view thereof;

FIG. 5 is an end elevational view thereof opposite that shown in FIG. 4;

FIG. 6 is a bottom plan view thereof.

FIG. 2

FIG. 1

FIG. 4

FIG. 3

FIG. 5

FIG. 6
